US00D782897S

(12) **United States Design Patent** (10) **Patent No.:** **US D782,897 S**
Harvey (45) **Date of Patent:** **** Apr. 4, 2017**

(54) **ATTACHMENT TO A HANDLE**

(71) Applicant: **Jonathan Neil Harvey**, Bluffdale, UT (US)

3,937,629 A 2/1976 Hamasaki
4,004,818 A 1/1977 Ramillon
4,641,857 A 2/1987 Gailunas

(Continued)

(72) Inventor: **Jonathan Neil Harvey**, Bluffdale, UT (US)

FOREIGN PATENT DOCUMENTS

(**) Term: **14 Years**

DE 202009004874 U1 12/2009
EP 1354793 A3 3/2003

U.S. PATENT DOCUMENTS

581,260 A 4/1897 Biddle
452,577 A 5/1897 Latta
587,626 A 8/1897 Vollmer
599,564 A 2/1898 Kinter

FIG. 1 is a side perspective view of an attachment to a handle;

FIG. 2 is a second side perspective view thereof;

FIG. 3 is a front side view thereof;

FIG. 4 is a back side view thereof;

FIG. 5 is a left view thereof;

FIG. 6 is a right side view thereof;

FIG. 7 is a top view thereof;

FIG. 8 is a bottom view thereof; and,

FIG. 9 is a second back side view thereof shown in environmental use.

The broken lines shown represent unclaimed subject matter and form no part of the claimed design.

1 Claim, 8 Drawing Sheets
